DASHBOARD BATTERY TESTER

Wilbur C. Dickinson, Reading, Pa.

Application August 26, 1955, Serial No. 37,672

Term of patent 14 years

(Cl. D52—1)

Fig. 1

Fig. 2

Fig. 3

Figure 1 is a top plan view of a dashboard battery tester showing my new design;

Figure 2 is a side view thereof; and

Figure 3 is a bottom view thereof.

I claim:

The ornamental design for a dashboard battery tester, substantially as shown.
